[57] **CLAIM**

The ornamental design for a paint receptacle having removable inserts, as shown and described.

DESCRIPTION

FIG. 1 is a perspective view of a paint receptacle showing my new design;

FIG. 2 is a perspective view of the paint receptacle of FIG. 1 with its cover removed, and revealing a set of removable inserts;

FIG. 3 is a perspective view showing the removable inserts of FIG. 2;

FIG. 4 is a perspective view showing one of the removable inserts of FIG. 2;

FIG. 5 is a perspective view showing the underside of the removable insert of FIG. 4;

FIG. 6 is a perspective view of the cover of FIG. 1;

FIG. 7 is a front elevation of the paint receptacle of FIG. 1;
FIG. 8 is a left side elevational view of the paint receptacle of FIG. 7;

FIG. 9 is a front elevational view of the paint receptacle of FIG. 7 with the cover removed;

FIG. 10 is a front elevational view of the removable insert of FIG. 4; and,

FIG. 11 is a left side elevational view of the removable insert of FIG. 4.
